SIGNOR OF ONE-THIRD TO C. C. WILLIAMS AND ONE-THIRD TO FRANK M. DYER,
OF DETROIT, MICHIGAN.

SAFETY-PIN.

1,112,098.

Specification of Letters Patent.

Patented Sept. 29, 1914.

Application filed April 3, 1913. Serial No. 758,619.

To all whom it may concern:

Be it known that I, FREDERICK C. SCOTT, a subject of the King of Great Britain, residing at Hornby Island, in the Province of 5 British Columbia and Dominion of Canada, have invented a new and useful Safety-Pin, of which the following is a specification.

The invention relates to improvements in safety pins.

10 The object of the present invention is to improve the construction of safety pins, and to provide a simple, inexpensive and efficient safety pin of strong and durable construction, equipped with means adapted with- 15 out weakening the pin proper or interfering with the ready passage or insertion of the same through a piece of fabric to interlock the said pin with a coacting catch or keeper and prevent the safety pin from be- 20 ing pulled open under a fair amount of strain.

With these and other objects in view, the invention consists in the construction and novel combination of parts hereinafter fully 25 described, illustrated in the accompanying drawing, and pointed out in the claims here- to appended; it being understood that various changes in the form, proportion, size and minor details of construction, within 30 the scope of the claims, may be resorted to without departing from the spirit or sacrificing any of the advantages of the invention.

In the drawings:—Figure 1 is a perspective view of a safety pin, constructed in accordance with this invention and shown closed. Fig. 2 is a longitudinal sectional view on the line 2—2 of Fig. 1. Fig. 3 is a transverse sectional view on the line 3—3 of 40 Fig. 1. Fig. 4 is a side elevation partly in section, one side of the catch or keeper being cut away. Fig. 5 is a plan view of a portion of the safety pin, illustrating the arrangement of the interlocking pin proper, and 45 the sides or jaws of the catch or keeper. Fig. 6 is a similar view, the lateral offsetting bend of the pin proper being in the opposite direction from that shown in Fig. 5.

Like numerals of reference designate cor- 50 responding parts in all the figures of the drawing.

In the accompanying drawing in which is illustrated the preferred embodiment of the invention, the body of the safety pin, which 55 is constructed of resilient wire or other suit-

able material, comprises in its construction a movable bar or pin proper 1 and a relatively fixed side or bar 2, connected with the movable bar or pin by a spring coil 3 and carrying a catch or keeper, which is connected with the relatively fixed side by a transverse end portion 4. The catch or keeper which consists of two lengths of wire spaced apart to allow for the introduction of the movable bar or pin proper, is composed of inwardly 60 extending approximately U-shaped loops 5 and 6, located at the free end of the catch or keeper and constituting jaws and adapted to frictionally engage the movable bar or pin proper 1 at opposite sides thereof, and the 65 said loops 5 and 6 extend from one side of the safety pin and terminate short of the opposite side of the same. The wire in the formation of the catch or keeper is extended longitudinally of the safety pin from one 70 terminal of the end portion 4 in substantial 75 parallelism with the relatively fixed side or bar 2, and is then bent to form the loop 6, which is connected at the outer portion with the loop 5. The wire is then extended back 80 to the end portion 4, the connecting portions 85 7 and 8 extending from the loops 5 and 6 to the end portion 4 are spaced apart and form a guard for the spaced end portion of the pin or bar 1. The terminal portion 9 of the 90 wire is twisted around the end portion 4, stiffening and thickening the latter opposite the point of the pin, the stiffened and thickened portion co-operating with the spaced 95 connecting portions 7 and 8 to prevent the 100 hand or other portion of a person from coming in contact with the pointed end of the pin or bar 1 when the safety pin is closed. The loops 5 and 6, which are disposed in substantial parallelism with the end portion 105 4, have spaced sides or engaging portions, and they are laterally offset from each other to arrange the coacting engaging sides or portions of the two loops in transverse planes arranged at different angles to the 110 movable pin or bar 1, as clearly illustrated in Fig. 2 of the drawing. The movable pin or bar 1 is provided near its pointed end with a bent portion 10, having spaced bends and a substantially straight intermediate 105 connecting portion disposed at an angle to the inner portion of the pin or bar and offsetting the outer pointed portion thereof from the longitudinal plane of the inner portion. The coacting sides or gripping por- 110

tions of the loops engage the pin or bar 1 at the said spaced bend and securely hold the said pin or bar 1. The short substantially straight angularly disposed connecting portion of the bend 10 forms a shoulder for interlocking the pin or bar 1 with the jaws of the catch or keeper to prevent the safety pin from being pulled open under a fair amount of strain. The loop 5 is slightly 10 narrower than the loop 6, and the inner sides of the loop engage the pin or bar 1 at the angle formed by the inner portion of the bend 10. The loops converge toward their 15 ends 11 and 12, which are diverged or bent in opposite directions to form a flaring entrance 13 to facilitate the easy introduction of the pin between the clamping jaws, which frictionally grip the pin and hold the same in its engaging position. The offsetting bend 10 while interlocking the pin or bar 1 with the catch or keeper does not weaken the former or interfere with the ready insertion of the pin through a piece of fabric.

20 25 The lateral offsetting bend may be extended in either direction, and in Fig. 6 of the drawing, the bend 14 extends in the opposite direction to the bend 10 and the loops 15 and 16 are arranged the reverse of the loops 5 and 6. While it is preferable to form the catch or keeper and the guard of a single piece of wire, any other equivalent construction may, of course, be employed for coacting or interlocking with the laterally bent pin.

30 35 What is claimed is:—

1. A safety pin including a movable bar or pin proper provided with spaced bends and a substantially straight intermediate angularly disposed connecting portion offsetting the outer portion of the pin from the plane of the inner portion, and a catch or keeper extending from a relatively fixed portion of the safety pin and having spaced 40 45 coacting gripping portions arranged in pairs which are spaced apart longitudinally of the safety pin to engage the movable pin or bar at the said bends thereof.

2. A safety pin including a movable bar or pin proper provided with spaced bends

50 55 and having a substantially straight intermediate angularly disposed connecting portion offsetting the outer portion of the movable pin or bar from the inner portion thereof, and a catch or keeper extending from a relatively fixed portion of the safety pin and comprising spaced coacting gripping portions arranged in pairs, the said pairs of gripping portions being disposed in transverse planes arranged at different angles to 60 the movable pin or bar and engaging the same at the bends thereof.

3. A safety pin including a movable bar or pin proper provided with spaced bends and having a substantially straight intermediate connecting portion offsetting the outer portion of the movable pin or bar from the plane of the inner portion, and a catch extending from the side of the safety pin at which the movable pin or bar is arranged 70 and terminating short of the opposite side of the safety pin, said catch consisting of a pair of substantially U-shaped loops having spaced sides or gripping portions, the sides or gripping portions of one loop coacting 75 with the sides or gripping portions of the other loop and the coacting gripping portions or sides being arranged in different transverse planes and engaging the pin or bar at the bends thereof.

4. A safety pin constructed of a single piece of wire and including a movable bar or pin proper having its end adjacent to the point deflected laterally and offsetting the point of the pin or bar from the remaining 80 85 portion of the same, and a catch or keeper composed of two lengths of wire spaced laterally to allow for the introduction of the pin or bar and formed at its free end with gripping portions arranged in pairs, which 90 are spaced longitudinally of the pin or bar so as to engage the same at two points along the deflected portion thereof.

In testimony that I claim the foregoing as my own, I have hereto affixed my signature 95 in the presence of two witnesses.

FREDERICK CHARLES SCOTT.
